APPARATUS FOR CONVERTING HYDROCARBONS

Dick S. Hall, Phillips, Tex., and Lloyd E. Dean, Chester L. Seyer, and Curt E. Forkel, Bartlesville, Okla., assignors to Phillips Petroleum Company, a corporation of Delaware

Application December 28, 1953, Serial No. 400,461

5 Claims. (Cl. 23—288)

This invention relates to a process and apparatus for effecting contact between fluids and solid particulate contact material. In one of its more specific aspects, it relates to an improved pebble heater reaction chamber. In another of its more specific aspects, it relates to an improved process for the conversion of hydrocarbons in a pebble heater reaction chamber wherein coke formation and deposition is reduced. In still another of its more specific aspects, it relates to a novel steam permeable expansion joint in the vapor effluent conduit of a pebble heater reaction chamber.

Apparatus of the so-called "pebble heater" type has been utilized in recent years for the purpose of heating fluids to elevated temperatures. Such apparatus is especially suited for use in temperature ranges above those at which the best-available high-temperature alloys fail. Thus, such equipment can be used for super-heating steam or other gases and for the pyrolysis of hydrocarbons to produce valuable products, such as ethylene and acetylene, as well as for other reactions and purposes. Conventional pebble-heater type apparatus includes two refractory-lined contacting chambers disposed one above the other and connected by a refractory-lined passageway or pebble throat of relatively narrow cross sections.

A principal use of pebble heating apparatus is in the conversion of hydrocarbons, involving thermal or catalytic processes, such as cracking, hydrogenation, dehydrogenation, isomerization, polymerization, and the like.

The term "pebble," as used herein, refers to the small pebble-like solid particulate refractory elements comprising the contact mass most generally used in pebble heating apparatus. Pebbles so used are preferably substantially spherical and relatively uniform in size, but in some instances they may be rod shaped or irregular in size. Spheres of about $\frac{1}{8}$ " to 1" in diameter function desirably, and those of about $\frac{1}{4}$ " to $\frac{1}{2}$ " are most practical. Pebbles as used herein comprise any solid refractory material of flowable form, size, and strength, suitable for carrying heat for transfer to gases in contact therewith. Pebbles comprising beryllia, alumina, zirconia, mullite, and periclase, for example, make excellent contact material for most processes. Metal balls, such as nickel, Monel, Inconel, iron, etc., have utility in specific processes. Pebbles and/or pebble surfaces may be catalytically active, or inert, to gases in contact therewith, depending on the specific process. For example, in non-catalytic cracking of a gas, the requisite is heat transfer and, therefore, an inert contact mass having a high heat-carrying capacity for transfer of heat to the gas in contact therewith is preferable. On the other hand, a catalytic gas conversion reaction would require the presence of a catalyst, in which case at least the pebble surface area would comprise the specific catalytic material needed.

In the operation of pebble heater apparatus, in many of the hydrocarbon-conversion processes, carbon is unavoidably formed and tends to deposit and accumulate

2

on the inner surfaces of the reactor to the extent that stoppage of flow of the reactants occurs and frequent shut-down periods result for the purpose of removing these carbon deposits. The pebble heater apparatus operates at extremely high temperatures; thus, the equipment is subject to thermal shock when heated to these high temperatures and then allowed to be cooled to atmospheric temperatures. It is at once apparent that the prevention of carbon deposits on the inner surface 10 of the pebble heater reactor chamber, so as to minimize shut-down periods, would result in a great savings, both in time and in expensive equipment.

We have found that carbon deposits can be greatly discouraged and, in many instances, completely prevented by the injection of steam into the pebble heater reactor chamber so that the surface which normally is subject to an accumulation of carbon is contacted with reactant gases containing a predetermined amount of steam.

15 20 We have devised means for supplying steam in the proper amounts to those inner surfaces of the reactor which tend to accumulate a deposit of carbon.

Each of the following objects will be attained by at least one of the aspects of the invention.

25 An object of this invention is to provide a method for controlling the deposition of coke on the inner surfaces of a pebble heater reactor chamber.

It is another object to provide an improved pebble heater reactor chamber.

30 35 It is still another object to provide a means for expansion and contraction of the vapor outlet conduit of a pebble reactor whereby the reactant vapors are confined within the outlet conduit.

It is still another object to provide a steam-permeable expansion joint in the vapor effluent conduit of a pebble heater reactor chamber.

Other and further objects and advantages will be apparent to those skilled in the art upon study of the accompanying discussion and the drawing.

40 Broadly speaking, this invention comprises an improved pebble reactor chamber having a load-supporting dome located in the upper portion of the chamber equipped with pebble conduit passageways located around the periphery of the dome and means for introducing steam into the interior of the dome through openings around the periphery of the dome. The steam can be supplied through the pebble conduit passageways or through openings around the periphery of the dome other than the pebble conduit passageways. The dome

45 50 55 is convex to the flow of pebbles and generally conforms to the angle of repose of the pebbles. The invention also comprises a steam-permeable expansion joint at the effluent-vapor outlet whereby vapors are prevented from leaking from the effluent conduit into the upper portion of the reactor chamber.

55 A better understanding of this invention will be obtained upon study of the accompanying drawing, wherein

Figure 1 is a schematic illustration of the pebble heater apparatus.

60 Figure 2 is a sectional elevation of a preferred form of the pebble heater reactor chamber of this invention.

Figure 3 is a sectional elevation of a modification of the reactor chamber of this invention.

65 Figure 4 is a sectional elevation of another modification of the reactor chamber of this invention.

Referring now to Figure 1 of the drawing, the operation of the pebble heater apparatus will be described. Pebbles are introduced into the upper portion of pebble heater 10 so as to form a contiguous gravitating mass of pebbles within that chamber. The pebbles are heated to a temperature well above the temperature required

for the desired reaction within the reaction chamber by combustion of a mixture of combustible material and combustion-supporting medium introduced from manifold 11 to the lower portion of pebble heater 10. The heated pebbles gravitate downwardly through throat 12, which communicates with the bottom of pebble heater 10 and the top of reactor 13. Reactant materials are introduced into the lower portion of reactor 13 through inlet 14; and pebbles, having given up their heat, gravitate downwardly from the lower portion of reactor 13 through conduit 15 to elevator means 16 and are returned through elevator 17 to pebble heater 10 so as to complete the cycle. Make-up pebbles are maintained in pebble storage 18.

Referring to Figure 2, pebble heater reactor 13 comprises upright, elevated shell 21 closed at its upper and lower ends by closure members 22 and 23, respectively. Pebble inlet conduit 12 is provided in the upper portion chamber 13, and steam inlet 24 is provided in the upper end of chamber 13. Load-supporting dome 25 is located in the upper portion of chamber 13 and is supported at its periphery by the refractory lining 26 of the chamber. A plurality of pebble conduits 27 are located around the periphery of dome 25, and a conduit 28 connects the interior of dome 25 to effluent conduit 29 located externally of the reactor chamber. A metal flange 31 connects the conduit 29 to the closed end 22 of the chamber. Flange 31 contains a ring 32 which extends a short distance into the closed end 22 of the chamber, and ring 32 has an inside diameter greater than the outside diameter of conduit 28 so that an annular space is provided between conduit 28 and ring 32. This annular space is packed with a compressible steam-permeable, refractory packing 33, for example, Fiberfrax (trademark). Fiberfrax (trademark) is fibrous aluminum silicate available from the Carborundum Company, Niagara Falls, New York. The annular space which results between conduit 28 and the refractory lining 26 of chamber 13 is also packed with this steam-permeable refractory packing.

We have found that the compressible fiber packing can be conveniently installed by placing the material in position around the conduit and securing it in position by wrapping thereupon a layer of cardboard prior to installing the conduit in the reactor chamber. The packing permits expansion and contraction of the conduit and reduces the amount of steam required to prevent the escape of vapors from the vapor-effluent line. A minor portion of the steam admitted to the reactor chamber through inlet 24 passes through the compressible packing at the expansion joint and is removed with the reactor effluent. A second and major portion of the steam travels downwardly with the gravitating pebbles and passes through the pebble conduit passageways at the periphery of the dome 25 and then proceeds upwardly along the inner surface of dome 25 and is removed with the reactor effluent.

Referring now to Figure 3 of the drawing, the reaction chamber is modified by providing a supplemental supply of steam which is added adjacent the pebble conduit passageways in the periphery of dome 25. The steam is supplied through a manifold 35 and is admitted to the interior of dome 25 through inlets 36. Through the use of this modification of the invention, additional steam can be supplied to the interior of the dome at a temperature lower than that of the pebbles and of the dome.

Referring to Figure 4 of the drawing, reaction chamber 13 is modified by providing an additional supply of steam through a manifold 37 consisting of a steam line in the form of a helix embedded in the refractory material of dome 25. Steam inlets 38 are in communication with manifold 37 and the interior of dome 25. This modification provides a device whereby heat can be added to, or removed from, dome 25 so as to provide greater flexibility in the operation of the reaction chamber.

We have found that by the injection of steam into the interior of the load-supporting dome in this reaction chamber, the deposition of carbon upon the inner surface of the dome can be substantially prevented and controlled.

5 The steam inlets which admit steam into the interior of the dome are preferably adapted so as to direct the steam onto the inner surface of the dome. It is sometimes advantageous to have the steam inlets spaced so that substantially the entire inner surface of the dome can be subjected to a moving film of steam.

Although this invention has been particularly described in connection with conversion of hydrocarbon reactant materials, the device can be advantageously employed for the purpose of superheating steam or for the fixation 15 of nitrogen or for conducting other reactions wherein large amounts of heat and high temperatures are required.

Variations and modifications are possible within the scope of the disclosure of the invention, the essence of which is the provision of an improved pebble heater reaction chamber wherein steam is added to the interior of a load-supporting dome located in the upper portion of the reactor so as to prevent the deposition of carbon thereon and the provision of a steam permeable expansion joint in the vapor effluent outlet.

25 We claim:

1. An improved reactor chamber of pebble heater apparatus comprising an upright, elongated, refractory lined shell; refractory lined pebble inlet means in the upper end of said shell; refractory lined pebble outlet means in the lower end of said shell; fluid inlet means in the lower portion of said shell; fluid outlet means at the top of said shell; steam inlet means in the upper portion of said shell; a refractory dome, convex to the flow of pebbles and conforming to the angle of repose of said pebbles, located coaxially in said chamber above said fluid inlet means and below said pebble inlet means supported at its periphery by the chamber wall; a steam manifold imbedded within the structure of said dome; steam inlet means connected to said manifold; a plurality 40 of steam pipe means connected to said manifold and projecting into the interior of the dome adjacent its periphery for supplying steam from said manifold to the zone within said dome in an amount sufficient to maintain a film of steam on the interior surface of said dome; a plurality of pebble conduit means at the periphery of said dome communicating between zones above and below said dome; a single fluid effluent refractory conduit of substantially uniform cross sectional area extending vertically from the upper end of the zone within said dome into the fluid outlet means at the top of said shell; and steam permeable, compressible refractory packing located in the annulus formed between said fluid effluent conduit and said fluid outlet means and between said fluid effluent conduit and the refractory lining of said shell.

2. An improved reaction chamber of pebble heater apparatus comprising a closed, upright, elongated, refractory lined shell; a single refractory lined pebble inlet means in the upper end of said shell; refractory lined pebble outlet means in the lower portion of said shell; refractory lined fluid inlet means in the lower portion of said shell; steam inlet means in the upper portion of said shell and spaced from said pebble inlet means; fluid outlet passageway through the refractory lining and chamber wall in substantially the center of the upper end of said refractory lined shell; a refractory dome, the upper surface of which is convex to the flow of pebbles and generally conforming to the angle of repose of pebbles, the lower surface of which is a smooth, nonangular collector concave to the flow of gases, located coaxially in said chamber below said pebble inlet means and above said fluid inlet means and supported at its periphery by the chamber wall; a plurality of pebble conduit means at the periphery of said dome communicating between zones above and below said dome; a single fluid effluent refrac-

tory conduit of substantially uniform cross sectional area extending vertically from the upper end of the zone within said dome into the fluid outlet passageway at the top of said shell; fluid withdrawal means connected to the fluid outlet passageway by a flange having an inside diameter greater than the outside diameter of said fluid effluent refractory conduit and extending partially through said refractory lined shell; and steam permeable, compressible, refractory packing material located in the annulus between said fluid effluent refractory conduit and said fluid outlet passageway and between said fluid effluent refractory conduit and said flange.

3. The reaction chamber of claim 2 wherein the steam inlet means is a conduit in communication with the interior of the refractory lined shell above the refractory dome.

4. The reaction chamber of claim 2 wherein the steam inlet means is a plurality of conduits communicating with the interior of said refractory dome at its periphery.

5. An improved reaction chamber of pebble heater apparatus comprising a closed, upright, refractory lined, elongated shell; a single, refractory lined pebble inlet means in the upper end of said shell; refractory lined pebble outlet means in the lower portion of said shell; refractory lined fluid inlet means in the lower portion of said shell; a refractory dome, convex to the flow of pebbles and conforming generally to the angle of repose of pebbles, located coaxially in said reaction chamber below said pebble inlet and above said fluid inlet and supported at its periphery by the chamber wall so as to form a first pebble bed in the upper portion of said reaction chamber; a plurality of passageways located around the periphery of said dome so as to permit passage of pebbles

10 to the zone below said dome to form a second pebble bed in the lower portion of said reaction chamber; steam inlet means in the upper portion of said shell and spaced from said pebble inlet means; fluid outlet means at the top of said shell; a single fluid effluent refractory conduit of substantially uniform cross sectional area extending vertically from the upper end of the zone within said dome, through said dome and into the fluid outlet means at the top of said shell; and a steam permeable, compressible, refractory packing located in the annulus formed between said fluid effluent refractory conduit and the refractory lining of said shell and between said fluid effluent refractory conduit and said fluid outlet means.
